(57) **CLAIM**

The ornamental design for a ligature resistant blind operator shroud, as shown and described.

DESCRIPTION

FIG. 1 is a left perspective view from above of a ligature resistant blind operator shroud;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left perspective view thereof, shown in its environment.

The broken lines shown in the drawings are for illustrating environment and form no part of the claimed design.
